UNITED STATES PATENT OFFICE

170,154

RUG OR SIMILAR ARTICLE

Magdalene R. Denes, New York, N. Y.

Application March 9, 1953, Serial No. 23,957

Term of patent 14 years

(Cl. D92—21)

To all whom it may concern:

Be it known that I, Magdalene R. Denes, a citizen of no country and residing at 327 West Eighty-fifth Street, New York city, county and State of New York, have invented a new, original, and ornamental Design for a Rug or Similar Article, of which the following is a specification, reference being had to the accompanying drawing, forming a part hereof, which is a plan view of a rug or similar article, showing my new design on a much reduced scale.

I claim:

The ornamental design for a rug or similar article, substantially as shown.

MAGDALENE R. DENES.
